WHIP STOCK LOCKING AND RELEASING APPARATUS

Robert P. Hanna, Box 362, Oak View, Calif.

Filed July 26, 1957, Ser. No. 674,492

7 Claims. (Cl. 166—117.5)

This invention relates generally to oil tools and more particularly to an improved whip stock and tool therefor adapted to be inserted between a string of drill pipe and a drill bit. This application is a continuation-in-part of my co-pending application, Serial Number 563,532 filed February 6, 1956 and entitled "Whip Stock Locking and Releasing Apparatus," now United States Patent No. 2,823,012.

In the lowering of conventional type whip stocks for the purpose of deflection drilling, there are often encountered projections or caves in the bore hole which tend to obstruct movement of the whip stock. The lower end of the whip stock extends beyond the normal mud passage outlet in the drill bit. Thus, while it is possible to circulate mud continuously through the pipe string and out the drill bit during the lowering process, the beneficial effects of this circulation in preparing a passage for the pipe string have little effect on the whip stock itself.

There is also encountered the difficulty of properly positioning the whip stock at the bottom of the bore hole in a desired orientation. Normally, the collar portion of the whip stock is supported by the end of the drill pipe string with one shear pin. After the whip stock is in position at the bottom or at an intermediate location in the bore hole, the pin is intentionally broken or sheared and the drilling is commenced. After the shear pin is broken, movement of the drill pipe string through the collar portion of the whip stock can often move the whip stock from its desired orientation, although once the drill pipe string has passed through and wedged the whip stock into tight engagement with the side walls of the bore hole, the whip stock will remain in its set position.

In addition to the above noted difficulties, present day whip stocks have a tendency to swing arcuately about the shear pin as a pivot point. Therefore, not only is the whip stock subject to becoming caught in cave portions of the bore hole side walls as a consequence of little or no mud circulation in the area of the whip stock, but further, this swinging tendency aggravates the problem of the whip stock becoming hung up by bridges and like obstructions during the lowering process.

Bearing the above in mind, one important object of the present invention is to provide an improved whip stock structure which co-operates with a holding tool to permit mud circulation to pass through the entire whip stock and out the tip whereby the lowering and positioning of the whip stock is greatly facilitated.

An equally important object is to provide an improved tool and whip stock combination for securing the whip stock to a drill pipe string while it is being lowered into a bore hole in a manner such that swinging movements and the possibility of the whip stock becoming dislocated after once being positioned in the bore hole are avoided.

More particularly, an object is to provide a whip stock locking and releasing apparatus which will hold the whip stock in a rigid position with respect to the drill pipe

2

string while it is being lowered into the bore hole, and which will retain the whip stock in its initially set orientation during the first downward movements of the string through the whip stock collar portion, and which additionally includes means for simultaneously altering the mud flow circulation path from one passing through the whip stock to one passing out the drill bit. As a consequence, once the whip stock is set in a desired position, it will remain substantially in such position and deflection drilling may progress with normal mud circulation.

Still another object of this invention is to provide a combination whip stock and tool therefor which may be operated from the surface of the bore hole for releasing the whip stock from the end of the drill pipe string once it has been lowered into a desired position on the bottom of the bore hole and for simultaneously changing the mud flow circulation as heretofore described.

15 These and many other objects and advantages of this invention are attained, briefly, by providing an improved whip stock and collar portion including a longitudinal mud circulation channel passing from the upper end of the collar portion to the lower end of the whip stock. 20 The inner annular wall of the whip stock collar portion is provided with a pair of axially spaced seals between which the upper end of the mud channel opens. The co-operating tool for holding the whip stock includes an elongated pipe section passing axially through the collar and provided with a lateral port normally positioned to open out between the annular seals on the whip stock collar whereby mud passing through the pipe section may 25 pass through this lateral port and down through the mud channel of the whip stock while the same is being lowered into the bore hole.

30 As in applicant's co-pending application above referred to, the exterior portion of the pipe section is also provided with one or more longitudinal lands adapted to be received in suitable longitudinal grooves on the inside 35 portion of the whip stock collar whereby relative rotation between the whip stock and pipe section is prevented during initial positioning of the whip stock. There are also provided laterally movable means interposed between the inside collar portion of the whip stock and the 40 pipe section adapted to be moved in response to the operation of actuating means within the pipe section through a lateral opening. Normally, this laterally movable means secures the pipe section and whip stock against relative axial movement during the lowering and 45 setting of the whip stock in the bore hole.

50 The actuating means itself within the pipe section is designed not only to move the laterally movable means upon actuation but also to alter the mud circulation flow path to block mud from passing through the whip stock channel after the whip stock has been set. Thus, upon 55 actuation of the actuating means within the pipe section, the laterally movable means is moved to free the pipe section for relative axial movement with respect to the whip stock. Simultaneously, the mud flow path is altered 60 to pass mud out of the drill bit. The longitudinal lands on the pipe section and longitudinal grooves in the whip stock collar are of sufficient axial extent that relative rotation between the whip stock and pipe section is prevented 65 during the initial movements of the pipe section through the whip stock collar such that when the lands have been moved sufficiently to be free of the grooves in the collar, the whip stock is thoroughly wedged in position and deflection drilling may then commence in a normal manner.

70 A better understanding of the various features and advantages of this invention will be had by referring to a

preferred embodiment thereof as illustrated in the accompanying drawings, in which:

Figure 1 is an enlarged cutaway perspective view of the improved whip stock portion of the present invention;

Figure 2 is a cross sectional view of the whip stock of Figure 1 in position about a pipe section illustrating the actuating means for locking and releasing the whip stock in a first position wherein the whip stock is securely held against relative rotational and axial movement with respect to the pipe section during the lowering thereof into the bore hole; and,

Figure 3 is another cross section identical to Figure 2 except that the actuating means is illustrated in a second position wherein the whip stock is free for relative axial movement with respect to the pipe section and the mud circulation path has been altered.

Referring to Figure 1, the details of the whip stock and collar will first be described. As shown, the whip stock comprises a conventionally shaped whip stock body 10 including the conventional wedge portion 11 indicated in dotted lines along its inner rear wall. In accordance with a first important feature of the present invention, this rear wall is provided with a longitudinal channel 12.

At the upper annular portion of the whip stock 10 and channel 12 there is provided a whip stock collar 13. As shown, the collar 13 includes a series of longitudinal grooves 14 on its inside annular wall terminating in shoulder portions 14' at their upper ends and opening into the interior of the whip stock 10 at their lower ends. These grooves are adapted to co-operate with suitable exterior lands on the whip stock tool holder to be described subsequently. Also included on the inside annular wall of the collar 13 is a pair of axially spaced sealing rings 15 and 16. Between these rings, the collar is recessed to define an annular passage 17 in fluid communication with the whip stock mud channel 12 through an upper end inlet opening.

Disposed axially above the annular passage 17 and circumferentially spaced at ninety degrees are a series of bores 19 passing through the annular wall of the collar, three of which are shown. These bores are exteriorly plugged as by plugs 20 and serve as receiving portions for partially receiving laterally movable means in the form of balls such as the ball 21. The whip stock collar 13 as thus described may be formed integrally with the whip stock body 10 or alternatively may be rigidly secured thereto as by welding at 22 and 23.

In Figure 2, the whip stock of Figure 1 is shown attached to a co-operating locking and releasing tool in turn adapted to be inserted between the end of a drill pipe string and drill bit. As shown, this tool comprises two basic components: first, an elongated longitudinal pipe section 24 passing axially through the whip stock collar 13 and terminating in a drill bit; and second, an actuating means in the form of a piston 25 longitudinally movable within the pipe section 24.

Referring first in detail to the pipe section 24, the upper end thereof is threadably secured to an adapter section 26 for attachment to the lower end of a pipe string. The lower end is provided with one or more exterior longitudinal lands 27. These lands are adapted to be received in the longitudinal grooves 14 of the whip stock collar 13 to lock the pipe section and whip stock against relative rotation so long as the lands are positioned in the grooves. The lower interior portion of the pipe section 24 includes a reduced diameter chamber 28 having a restricted neck portion at its upper end and an outlet mud passage 29 at its lower end. This mud passage communicates with a conventional drill bit 30 threadedly connected to the pipe section 24 as at 31.

The central portion of the pipe section 24 widens out into a uniform diameter cylinder portion 32 throughout the remaining length of the pipe section and defines an annular shoulder 33 at the upper end of the chamber 28.

Passing through the side wall of the pipe section 24 above the annular shoulder 33 is a lateral port 34 communicating with the annular passage 17 defined by the interior annular wall portion of the whip stock collar 13 between the axially spaced pair of seals 15 and 16 and the exterior of the wall portion 32 of the pipe section 24. Thus, mud flowing out the outlet port 34 is confined within the annular passage 17 by the spaced seals but may flow about this annular passage to pass into the upper end of the channel opening 18 of the whip stock channel 12 regardless of the relative initial rotative position of the whip stock and pipe section.

Disposed above the port opening 34 in the pipe section side wall 32 are further lateral openings such as the opening 35 registering with the receiving bore opening 19 for the ball 21 in the whip stock collar 13. The arrangement is such that the ball 21 partially extends into this lateral opening in the side wall of the pipe section as shown. The extreme upper end of the pipe section is threaded as at 36 to the adapter section 26.

Referring now in detail to the second basic component of the tool, the piston 25 includes a central mud passage 37 terminating at its extreme lower end in a ball check valve 38. Spaced above this lower end are lateral mud port openings such as indicated at 39 substantially even with the lateral port opening 34 in the side wall 32 of the pipe section when the piston 25 is in the first position illustrated in Figure 2. Above the lateral ports 39 there is provided a first enlarged diameter flange 40 positioned to abut or block the balls 21 when the piston 25 is in the position illustrated in Figure 2. In this position, the lower end of the flange defines with the annular shoulder 33 an annular space. By this arrangement, mud passing down the central mud passage 37 of the piston will pass out the lateral ports 39 into this annular space and thence through the ports 34 into the annular passage 17 and down the mud channel 12 of the whip stock.

Axially spaced above the annular flange 40 is a second enlarged diameter annular flange 41. The flanges 40 and 41 define an annular recess therebetween with the inside of the pipe section wall 32 as shown. This recess is dimensioned to receive the ball 21 when the piston 25 is moved from the position illustrated in Figure 2 to a second position as will be described in connection with Figure 3. The first and second enlarged diameter flanges 40 and 41 are provided with peripheral sealing rings as indicated whereby mud passing out the lower lateral ports 39 of the piston 25 is blocked from entering the annular recess defined between these flanges.

Above the second enlarged diameter annular flange 41, the piston extends into the adapter section 26 and is normally secured in its first position to this adapter section as by shear pins 42 and 43. The upper end portion of the piston 25 includes lateral mud ports 44 and terminates in a ball seating surface 45. The adapter section 26 includes an enlarged diameter chamber portion 46 arranged to be placed in communication with the upper lateral mud ports 44 when the piston 25 is in a second position as will become clearer as the description proceeds. The extreme upper end of the adapter section 26 terminates in threads 47 adapted to be threadably connected to the end of a conventional drill pipe string.

From the physical description of the various components and their relative positions described in connection with Figure 1, it will be evident that the whip stock 10 is secured first against relative rotation with respect to the pipe section 24 by means of the exterior longitudinal lands 27 positioned within the grooves 14 of the whip stock collar. Relative axial movement is also prevented between the whip stock and the pipe section as a consequence of the balls 21 partially extending into the pipe section lateral openings 35 and the receiving bores 19 of the whip stock collar. The radial inward extent of the plugs 20 in the whip stock collar may be adjusted such that the balls 21 are partially extended in

the lateral openings of the pipe section a desired distance. Preferably, this distance is such that the center of the balls 21 extend beyond the plane of the lateral openings 35. It will also be evident from Figure 2 that the first enlarged diameter annular flange 40 abuts against the balls 21 such that they are securely held in the position illustrated. The whip stock is accordingly held against both rotative and axial movement with respect to the pipe section and in the position illustrated, is ready for lowering into a bore hole.

In operation, during the lowering process, mud is circulated through the drill pipe string to pass into the upper end of the adapter 26 and through the central mud passage 37 of the piston 25 as indicated by the arrows. As shown, the mud passes on down through the central mud passage 37 and out the lateral ports 39 into the annular space defined between the lower end of the first enlarged annular flange 40 and the annular shoulder 33 defined by the upper end of the chamber 28. From this annular space, mud then flows through the lateral ports 34 into the annular passage 17 defined by the collar portion 13, and through the upper end opening 18 of the whip stock mud channel 12. Mud passes down through this channel and out the end of the whip stock whereby any possible obstructions to the passage of the whip stock through the bore hole are substantially cleared by mud circulating from the tip. The process of lowering the whip stock into the bore hole is thus greatly facilitated by this novel mud circulation arrangement.

The whip stock itself is thoroughly locked to the pipe section and thus is not subject to arcuate swinging or otherwise moving in a manner such that it may become caught in caves or the like.

When the position within the bore hole has been reached wherein a deflection bore is to be started, the lowering of the pipe string is stopped and the setting of the whip stock may then proceed. In order to unlock the whip stock from the pipe section, the actuating means in the form of the piston 25 is caused to move from the first position illustrated in Figure 2 to the second position illustrated in Figure 3. This movement is effected from the surface of the bore hole by dropping a small ball 48 as illustrated in Figure 3 through the drill pipe string to pass into the upper end of the adapter section 26 and fall in the ball seat 45 at the upper end of the piston 25. When the ball 48 is received in the ball seat 45, the mud circulation through the central mud passage 37 of the piston is blocked and pressure will build up in the upper part of the adapter section. After the pressure has built up to a given value sufficient to shear the shear pins 42 and 43, the piston 25 will be moved longitudinally downwardly to the position illustrated in Figure 3. In this position, the upper end of the piston is received in the enlarged diameter chamber 46 whereby mud may again circulate through the central mud passage 37 by passing through the mud ports 44 as indicated by the arrows.

In this second position of the piston 25, it will be noted that the underside of the first enlarged diameter annular flange 40 has seated against the annular shoulder 33 of the pipe section 24, and this shoulder thus serves as a stop means for movement of the piston. As a further consequence of this movement, the annular recess defined between the first and second flanges 40 and 41 has moved down into a position level with the lateral opening 35 in the pipe section side wall such that the balls 21 fall into this annular recess as indicated by the dotted arrows in Figure 3. Simultaneously, movement of the first annular flange 40 into seating relationship with respect to the annular shoulder 33 of the pipe section moves the lateral ports 39 from a position formerly in communication with the lateral ports 34 of the pipe section into the reduced diameter chamber 28 in the lower portion of the pipe section. Mud flow passing down the central mud passage 37 is thus blocked from passing out of the lateral ports 34 of the pipe section and caused to pass

out the ports 39 into the chamber 28 in the lower portion of the pipe section and thence on down through the drill bit mud passage 29 out the end of the drill bit 30 as indicated by the arrows in Figure 3.

After the piston 25 is in the second position illustrated in Figure 3 wherein the balls 21 fall into the annular recess between the first and second flanges 40 and 41, the pipe section 24 is free for relative axial movement with respect to the whip stock 10 and collar portion 13. Thus, lowering of the pipe string will now move the pipe section axially through the collar portion a given distance. In this latter described movement, the longitudinal lands 27 on the outside of the pipe section will slide downwardly along the grooves 14 in the whip stock collar portion and during this initial movement relative rotation between the whip stock and the pipe section will still be prevented. This initial movement, however, will serve to lodge the whip stock into the surrounding formations without any possibility of the angular orientation of the whip stock changing. Continued movement of the pipe string downwardly will ultimately cause the exterior lands 27 to pass from the lower ends of the grooves in the collar and thus free the pipe section for relative rotation with respect to the whip stock. The drilling of the deflection bore may thus commence in the desired direction as determined by the initial orientation of the whip stock and mud may be circulated in a conventional manner.

When the whip stock is to be removed, the drill pipe string is simply raised up until the lands 27 on the pipe section engage the upper end shoulders or the grooves or, if the relative rotational positions between the whip stock and pipe section are not such that the lands will be received in the grooves, the upper ends of the lands will simply engage the underside of the collar 13 to lift the same upwardly. The purpose for the lower ball check 38 at the extreme end of the piston member 25 is to enable conventional reverse mud circulation to be effected, if desired when the piston 25 is in the first position illustrated in Figure 2.

It will be evident from the above description that the present invention provides a greatly improved whip stock and whip stock locking and releasing tool in which the same may be controlled from the surface of the bore hole by means of the drop ball 48 and mud pressure and in which a single actuation of the actuating means in the form of the piston 25, serves to both unlock the pipe section and whip stock for relative axial movement and alter the mud circulation path whereby mud is circulated out the drill bit in a normal fashion.

Various modifications within the scope and spirit of the present invention will readily occur to those skilled in the art. The improved whip stock and tool is, therefore, not to be thought of as limited to the specific embodiment set forth for illustrative purposes.

What is claimed is:

1. A whip stock comprising: a collar portion; at least two axially spaced annular seals disposed above the interior wall of said collar portion; and channel means defining a mud passage having an upper end opening between said seals and passing down said whip stock to open out of the lower end thereof, said collar portion being adapted to surround a pipe section having a lateral mud port opening between said seals whereby mud passing through said port opening is confined by said seals to flow through said channel means, a portion of the interior wall portion between said seals on said collar portion being recessed to define in cooperation with the outer walls of said pipe section an annular passage so that said port opening is in communication with said upper end opening of said channel means for all relative rotative positions between said collar portion and said pipe section.
2. A whip stock tool comprising, in combination: a whipstock having a collar formed at its upper end and including a mud channel having an upper end opening in

said collar and passing to a lower end opening of said whip stock; a pipe section passing axially through said collar and having a lateral mud port in communication with said upper end opening of said mud channel; an inter-engaging means on said pipe section and collar for locking said pipe section and collar against relative rotation; laterally movable means interposed between said collar and said pipe section, a portion of said laterally movable means engaging said collar, said pipe section including a lateral opening above said lateral mud port within which an opposite portion of said laterally movable means projects for locking said collar and pipe section against relative axial movement; an elongated piston longitudinally movable within said pipe section from an upper first position to a lower section position, said piston including an enlarged diameter annular flange having a reduced diameter region above the upper end of said annular flange sufficient to accommodate said laterally movable means, said annular flange being juxtaposed said lateral opening when said piston is in said first position to hold said laterally movable means partially within said lateral opening, said pipe section including a reduced diameter chamber in its lower portion having a mud passage extending therefrom out of the bottom of said pipe section, said chamber defining an upper annular shoulder axially spaced below said annular flange when said piston is in said first position to define with said annular flange an annular space communicating with said lateral mud port, said piston including a central mud passage having an upper entrance portion and a lower exit opening into said annular space when in said first position so that mud passing down through said mud passage flows into said annular space and out through said lateral mud port to said upper end opening of said mud channel in said whip stock, movement of said piston from said first position to said second position positioning said annular flange below said lateral opening to release said laterally movable means for movement from said collar completely through said lateral opening into said region above said annular flange thereby permitting relative axial movement of said pipe section with respect to said collar, said annular flange also seating on said annular shoulder in a position juxtaposed said lateral mud port when said piston is in said second position to block the flow of mud through said lateral mud port, said lower exit opening in said piston extending below said annular shoulder to communicate with said reduced diameter chamber in said pipe section so that mud flows downwardly out the bottom of said pipe section, whereby said mud flow through said

channel and said whip stock is cut off and diverted to flow out the bottom of said pipe section.

3. A whip stock tool according to claim 2, in which said laterally movable means comprises a ball member which is received within said region of said pipe section above said annular flange upon downward movement of said piston from said first to said second position.

4. A whip stock tool according to claim 2, including lateral shear pins securing said piston to said whip stock tool in said first position; and closure means to block temporarily said upper end entrance portion of said mud passage in said piston whereby said mud pressure is built up sufficiently to shear said shear pins and initially move said piston from said first position towards its second position.

10 5. A whip stock tool according to claim 4, in which said closure means comprises a ball seat formed at said upper end entrance portion of said mud passage and a ball adapted to be dropped into position on said ball seat to block said mud passage.

20 6. A whip stock tool according to claim 5, including an adapter section threadably secured to the upper end of said pipe section in a position to surround the upper end of said piston in fluid tight relationship when said piston is in said first position, said adapter having an increased diameter portion into which the upper end of said piston moves when in said second position, said upper end of said piston having a lateral mud opening below said ball seat, whereby mud may commence flowing through said adapter section, into said increased diameter portion, through said lateral mud opening, and down said central mud passage after said piston is in said second position.

25 7. A whip stock tool according to claim 6, including a drill bit connected to the lower end of said pipe section and an outlet mud passage for passing mud from said chamber in the lower portion of said pipe section to said drill bit when said piston is in said second position.
